UNITED STATES PATENT OFFICE.

EDWARD E. HERRINTON AND GEORGE W. IRISH, OF GRAND LEDGE, ASSIGNEES OF ONE-FOURTH TO HIRAM O. ROSE, OF PETOSKEY, MICH.

CAR-COUPING.

SPECIFICATION forming part of Letters Patent No. 247,759, dated October 4, 1881.

Application filed April 29, 1881. (No model.)

To all whom it may concern:

Be it known that we, EDWARD E. HERRINTON and GEORGE W. IRISH, of Grand Ledge, in the county of Eaton and State of Michigan, have invented a new and useful Improvement 5 in Car-Couplings, which improvement is fully set forth in the following specification and accompanying drawings, in which—

Figure 1 is a sectional view, showing pin B resting on gravitating tongue C, in position for coupling the cars automatically when run together. Fig. 2 is a sectional view of our improved car-coupling, with link d resting in inclined groove b, Fig. 3, which is held in position for entering opposite draw-head by gravitating tongue C falling and resting upon it of its own weight. Fig. 3 is a sectional view, showing the bottom of the chamber of the draw-head, in which is a groove for receiving the link and holding the same at an angle sufficient to cause it to enter at the center of the opposite draw-head. The groove b is depressed from the front backward. Fig. 4 is a top view of tongue C, showing journals upon which it hangs upon either side and at the top of the pin-hole S. Fig. 5 is a side view of same.

Similar letters of reference indicate corresponding parts.

Our object is to combine such feature of con-

struction in connection with the ordinary pin 30 and link as will cause the cars to couple automatically when run together.

To couple the cars automatically with our improved car-coupling, the link d is first placed in position, as shown in Fig. 2, by dropping 35 same into the groove b, Fig. 1, which is thus held in position by gravitating tongue C resting upon it of its own weight. As the cars are run together the link d strikes and presses back the tongue C, upon which rests coupling-pin 40 B, Fig. 1, which causes the coupling-pin B to fall through the link d, thus coupling the cars.

Having thus described our invention, what we claim as new, and desire to secure by Letters Patent, is—

The manner of pivoting the gravitating tongue C inside the draw-head instead of above it, thus avoiding the slot, in combination with the inclined and grooved bottom of chamber b, Figs. 1 and 3, and gravitating tongue C, 50 Figs. 1 and 2, substantially as shown and described.

EDWARD E. HERRINTON.
GEORGE W. IRISH.
